BUCKLE

Merle J. Adams, Scarsdale, N. Y., assignor to
Knothe Brothers Co., Inc., New York, N. Y., a
corporation of New York

Application May 4, 1953, Serial No. 24,842

Term of patent 14 years

(Cl. D17—1)

To all whom it may concern:

Be it known that I, Merle J. Adams, a citizen of the United States of America, residing at Scarsdale, in the county of Westchester and State of New York, have invented a new, original, and ornamental Design for a Buckle, of which the following is a specification, reference being had to the accompanying drawing, forming a part hereof.

Figure 1 is a front face view of the buckle embodying my new design;

Fig. 2 is a rear view of the buckle;

Fig. 3 is a longitudinal sectional view taken on line 3—3 of Fig. 1 and illustrating the buckle in closed condition; and

Fig. 4 is a view similar to that of Fig. 3 and illustrating the buckle in its open condition.

The characteristic feature of the design resides in the tongue member having a divided hinge sleeve, a centralized projection, and indentations on both the upper and lower edges, in combination with the frame member as shown.

I claim:

The ornamental design for a buckle, as shown and described.
